UNITED STATES PATENT OFFICE.

ANTHONY COSEGLIA, OF WEST HOBOKEN, NEW JERSEY, ASSIGNOR, BY MESNE ASSIGNMENTS, TO AUTOSALES CORPORATION, A CORPORATION OF NEW YORK.

COIN-CONTROLLED VENDING MACHINE.

Application filed August 18, 1917. Serial No. 186,843.

To all whom it may concern:

Be it known that I, ANTHONY COSEGLIA, a subject of the King of Italy, and a resident of West Hoboken, in the county of 5 Hudson, in the State of New Jersey, have invented certain new and useful Improvements in Coin-Controlled Vending Machines, of which the following is a specification.

10 My invention relates to coin-controlled vending machines, and has for its object the provision of a machine of small dimensions, especially adapted for use in theatres and other places where but little space is available for accommodating such machines. The machine of my invention is particularly, although not exclusively, adapted for the sale of cylindrical packages of confection or other commodity.

15 The various features of novelty which characterize my invention will become apparent from a detailed description of the accompanying drawings which illustrate a preferred embodiment of my invention.

20 In these drawings,

Fig. 1 shows a rear view of a machine embodying my invention, the back wall of the casing being removed to show the interior parts, and the parts being in normal 30 position;

Fig. 2 is a side view in section taken on line 2—2 of Fig. 1, looking in the direction of the arrows;

Fig. 3 is a transverse cross-section on line 3—3 of Fig. 1, looking downwardly;

Fig. 4 is a transverse cross-section on line 4—4, looking downwardly;

Fig. 5 is a fragmentary detail view showing how the coin-operated lever and the 40 slide bar for the delivery member enter into locking engagement with each other under certain conditions;

Fig. 6 is a rear view of the machine, showing the coin-controlled mechanism in position after ejecting the lowermost package;

Fig. 7 is a longitudinal cross-section on line 7—7 of Fig. 6, looking in the direction of the arrows; and

Fig. 8 is a fragmentary detail view showing the coin-receptacle into which drop the discharged coins.

The outer casing of the machine is preferably constructed in two sections—a front section A and a rear section B. The front 55 section A comprises a front plate 1, side

pieces 2, and a bottom 3 which terminates at the point indicated at 4 in Figs. 2 and 7.

The rear section B of the casing consists of a rear plate 5, a top 6, side flanges 7 and a bottom flange 8. The top 6 is provided with a front flange 9 which meets the plate 1 of the front section on the line indicated at 10 in Figs. 2 and 7.

When the two sections A and B are assembled, the side pieces 2 of the front section A abut against the side flanges 7 of the rear section B along the line indicated at 11 in Figs. 2 and 7. In this way a closed casing is formed. The two sections are held locked together by any suitable locking mechanism, which I have not deemed necessary to show, as it forms no part of my invention.

Within the casing is mounted the goods-compartment or magazine indicated as a 75 whole by M. This magazine is preferably formed out of sheet metal and comprises a front wall 12, rearwardly extending side walls 13 and 14, and inwardly extending rear flanges 15. The magazine M is secured to the removable front section of the casing by being pivoted, as shown at 16, to the side pieces 2 of the section A. By being thus pivoted near its upper end, the magazine may be readily swung out of the casing 80 whenever desired, as indicated by the dotted lines M' in Fig. 7.

In order to allow a limited rearward movement of the magazine M, as when it is desired to remove the deposited coins (as will hereinafter be more 90 fully explained), the side wall 13 of the magazine is provided with a slot 17 in which engages a button 18 formed in one of the side pieces of the front section A, as best shown in Fig. 3. This construction allows a slight rearward swinging of the magazine without interfering with the full rearward movement thereof, as the button will ride out of the slot 17 when the magazine is swung into the position shown in 95 dotted lines in Fig. 7.

The magazine M is adapted to contain packages P which are shown in the drawings as cylindrical in form. The flanges 15 prevent the packages from falling rearwardly 100 out of the magazine.

Below the magazine M is mounted the delivery member indicated as a whole by D. This member is cylindrical or trough-shaped in form, being adapted to receive the pack- 110

ages P. For the sake of convenience, I will hereinafter call the member D the delivery cylinder. I do not, however, mean to imply by this that the member D must be strictly 5 cylindrical in form, it being only necessary that it be so constructed as to receive the packages P, of whatever form or size they may be. The delivery cylinder D, in the form illustrated, consists of a semi-cylindrical 10 shell-member 19 and side disks 20 and 21. The shell-member 19 is adapted to receive the lowermost package when the cylinder D is in normal position. The disks 20 and 21 are provided with pivot pins or studs 22 and 23, 15 by means of which the delivery cylinder is pivoted in the side members 2 of the front section A, as best shown in Fig. 4. To the side disk 21 of the delivery cylinder D is secured a pinion 24 by means of pins 25 or 20 otherwise.

The teeth of the pinion 24 mesh with the teeth 26 of the rack bar 27 which is part of, or secured to, the actuating slide 28. This 25 slide is mounted to reciprocate vertically and oscillate the delivery cylinder D. The slide 28 is mounted on one of the side walls 2 of the front section A of the casing by means of pins or studs 29, which engage in slots 30 of the slide 28. The actuating slide 28 30 is normally held in uppermost position, as shown in Fig. 2, by the contractile spring 31. The lower end of the spring 31 is fastened to the lug 32 at the upper end of the slide 28, while the upper end of the spring is secured 35 to the lug 33 carried by the front section A.

By reference to Figs. 1 and 2, it will be 40 seen that when the actuating slide 28 is in normal position, the delivery cylinder D is in such position that the semi-cylindrical shell 19 is in goods-receiving position. In other words, when the delivery cylinder is in normal position, the lowermost package rests within it, as indicated at P¹ in Fig. 1. When the actuating slide 28 is moved downwardly, by mechanism to be presently described, the delivery cylinder is rotated into the position shown in Fig. 7, thereby discharging the bottom package P¹ into the delivery chamber 34 at the bottom of the casing. This delivery chamber has side 50 openings 35, through which the package may be withdrawn. A suitable guiding plate 36 may be provided for guiding the ejected package into the delivery chamber. To facilitate the removal of the delivery package, the front wall 1 of the casing is preferably provided with cut-away portions 37, as indicated in Fig. 1.

When the cylinder D is in delivery position, as seen in Fig. 7, the packages in the magazine are supported on top of the semi-cylindrical shell-member 19. When the actuating slide 28 returns to normal or upper position under the influence of spring 31, 65 the delivery cylinder D is rotated back-

wardly to normal position. As soon as the outer surface of the shell member 19 slides from under the column of goods, the lowermost package drops down into the hollow shell-member 19.

The front wall 1 of the section A of the casing is provided with a pin or stud 38 on which is pivoted the bell-crank lever 39. The arm 40 of this lever is at its outer end provided with a pin 41 to which is secured one 70 end of a contractile spring 42. The other end of this spring is secured to any fixed part of the casing, as the lug 43. By means of the spring 42, the bell-crank lever 39 is normally held in the position shown in 75 Fig. 1. A fixed stop 44, carried by the front wall of the casing, limits the movement of lever 39 under the action of spring 42. The laterally extending arm 45 of the bell-crank lever 39, is at its outer end provided with a 80 pin or projection 46 adapted to engage in the slot 47 formed in the extension 48 of the slide 28.

Any suitable coin-controlled mechanism 85 may be employed for actuating the bell-crank lever 39. For the sake of illustration, I have shown in the drawings a coin-carrier 49 mounted to rotate in the coin-passage 50. A suitable member, such as a knob 51, is operatively connected with the coin-carrier 90 95 95 to rotate the same and carry the coin into operative position within the machine. The pin 41 of the bell-crank lever 39 extends into the coin-passage 50 through the slot 52 formed in the front plate 1 of the casing. 100

When a proper coin is deposited into the coin-entrance slot 53, which is arranged at the top of the casing, and the coin-carrier rotated by means of the knob 51, the coin is carried through the coin-passage 50 105 until it strikes the pin 41 of the lever 39. In Fig. 1, the position of the coin is indicated in dotted lines at C¹. During this movement, the coin has depressed the spring-pressed slide 54, the purpose of 110 which is to lock the coin against return movement after it has been carried into the machine a predetermined distance. As the coin-carrier is further rotated, carrying the deposited coin with it, the bell-crank 115 lever 39 is rocked from the position shown in Fig. 1 to that shown in Fig. 6. During this movement of the bell-crank lever 39, the slide 28 is pushed downwardly from the position shown in Fig. 2 to that shown 120 in Fig. 7. During this operation of the slide 28, the delivery cylinder D ejects the lowermost package, as already explained in detail.

It will be clear from Fig. 6, that as the 125 coin-carrier is rotated further, the coin C¹ will pass out of engagement with the pin 41 and drop rearwardly through the opening 55 into the coin receptacle 56 arranged between the lower end of the magazine and 130

the front plate 1, as best shown in Figs. 7 and 8. This coin receptacle comprises a strip 57 secured to the front plate 1 of the casing. Between the strip 57 and the side wall 2 of the casing is a space or opening 58, which is normally covered by the member 59 carried at the lower end of the magazine M. For convenience of construction, the member 59 may be formed as a 10 forwardly projecting flange at the lower end of the front wall 12 of the magazine M, as indicated in Fig. 8. The movable member 59 is arranged below the fixed coin-supporting strip 57. In Fig. 1, the deposited 15 coins which have been discharged from the coin-carrier and which rest in the coin receptacle 56, are indicated at C². To release the coins, it is only necessary to swing back the magazine as far as the slot 17 and the 20 button 18 will allow. This slight movement of the magazine carries the flange member 59 out of coin-supporting position, and by slightly tipping the machine, the coins will roll out of the space or opening 58.

25 In order to prevent the coins from accidentally clinging to the front wall 12 of the magazine, I provide a stripper 60 which is carried by the strip 57 and which prevents the coins from following the magazine as it is swung rearwardly, thereby insuring their falling through the opening 58.

To prevent operation of the machine when the supply of goods is exhausted, I provide means for locking the bell-crank lever 39 against operation. A pawl 61 is pivoted at 62 to the front plate 1 of the casing. The pawl 61 is at its lower end provided with a locking shoulder 63. A spring 64 tends 40 to force the pawl 61 toward the delivery cylinder D. When there is a package of goods in the cylinder it engages the pawl 61 at the projection 65 and thereby holds the locking shoulder 63 out of locking engagement with the edge of the semi-cylindrical shell 19. So that, as long as there are any goods in the machine, the pawl 61 does not interfere with the ejecting operation of the delivery cylinder. However, when 45 the last piece of goods has been ejected and the delivery cylinder has returned to normal position under the action of the spring 31, the spring-pressed pawl 61 is thrust rearwardly into positive locking engagement 50 with the delivery cylinder D, as shown in Fig. 2. This locks the cylinder D, the slide 28 and the bell-crank lever 39 against operative movement. Should, under these conditions, a coin be deposited in the machine 55 and the coin-carrier rotated, the coin will go no farther than indicated at C¹ in Fig. 1 (except for the loose play allowed between the pin 46 and slot 47), and the bell-crank lever 39 is locked against forward movement. While the deposited coin is thus

locked against further inward movement, the coin-carrier 49 is free to be rotated reversely, so that the intending purchaser may remove his coin through the coin-slot 53. In this way, an intending purchaser is sure 70 of the return of his coin when the machine is empty.

In order to prevent tampering with the machine in an effort to secure a package of goods without the deposit of a coin, I provide means for locking the delivery cylinder when an effort is made to operate it from below, as by the insertion of an instrument through the delivery chamber at the bottom of the casing. By referring to Figs. 1 and 5, it will be seen that the lateral extension 48 of the slide 28 is formed with a shoulder 66, while the pin 46 of the bell-crank 39 is formed with a shoulder 67. When an attempt is made to operate the delivery cylinder D or the slide 28 from below, a slight downward movement of the slide 28 will bring the shoulders 66 and 67 into positive locking engagement, as indicated in Fig. 5, 85 thereby locking the slide 28 and the delivery cylinder D against operative movement. As an additional precaution, I may provide the extension 48 with a second shoulder 68, so that, should the shoulder 66 for any reason fail to lock with the shoulder 67, the shoulder 68 will come into action. 90

Although I have herein shown and described a specific form of machine embodying the various features of my invention, I will have it understood that I am not to be limited to such details of construction. It is obvious to those skilled in the art that in the broader aspect of my invention, the various features of novelty, as pointed out in the claims, may be mechanically carried out 100 in other forms than those shown and described. 105

Having thus described my invention what I claim as new, and desire to secure by Letters Patent of the United States, is: 110

1. In a vending machine, a casing having a magazine for containing the vendable articles, a delivery cylinder pivoted below said magazine for ejecting the bottom article, a reciprocable slide connected with said cylinder for actuating the same into delivery position, said slide having a slot provided with a shoulder, a pivoted lever having a pin to engage said slot and thereby actuate said slide when the lever is operated, means for manually operating said lever from the outside of the casing, and a shoulder on said pin for interlocking with said first named shoulder to lock said slide against operative movement, when an attempt is made to operate said slide otherwise than through said lever. 115

2. In a vending machine, a casing having a magazine for containing the vendable articles, a delivery cylinder pivoted below said 120

magazine for ejecting the bottom article, a reciprocable slide connected with said cylinder for actuating the same into delivery position, a pivoted lever adapted to be manually operated from the outside of the casing, and co-operating means on said lever and said slide for transmitting the movement of said lever to said slide, said co-

operating means positively locking said slide against operative movement when an attempt is made to operate said slide otherwise than through said lever.

In witness whereof, I hereunto subscribe my name this 3rd day of August, 1917.

ANTHONY COSEGLIA.
